(57) **CLAIM**

The ornamental design for shears, as shown and described.

DESCRIPTION

FIG. 1 is a front perspective view of shears showing our new design in a closed position;

FIG. 2 is a right side view thereof;

FIG. 3 is a left side view thereof;

FIG. 4 is a top view thereof;

FIG. 5 is a bottom view thereof;

FIG. 6 is a front view thereof; and

FIG. 7 is a rear view thereof.

FIG. 8 is a front perspective view of the shears of FIG. 1 in an opened position;

FIG. 9 is a right side view thereof;

FIG. 10 is a left side view thereof;

FIG. 11 is a top view thereof;

FIG. 12 is a bottom view thereof.

FIG. 13 is a front view thereof; and,

FIG. 14 is a rear view thereof.

The features shown in broken lines are portions of the shears forming no part of the claimed design.

1 Claim, 9 Drawing Sheets
